(No Model.)

G. EASTMAN.
ROLLER HOLDER FOR PHOTOGRAPHIC FILMS.

No. 433,775.

Patented Aug. 5, 1890.

UNITED STATES PATENT OFFICE.

GEORGE EASTMAN, OF ROCHESTER, NEW YORK, ASSIGNOR TO THE EASTMAN DRY PLATE AND FILM COMPANY, OF SAME PLACE.

ROLLER-HOLDER FOR PHOTOGRAPHIC FILMS.

SPECIFICATION forming part of Letters Patent No. 433,775, dated August 5, 1890.

Application filed June 12, 1889. Serial No. 314,052. (No model.)

To all whom it may concern:

Be it known that I, GEORGE EASTMAN, of the city of Rochester, county of Monroe, and State of New York, have invented certain new and useful Improvements in Roll-Holders for Photographic Films; and I do hereby declare the following to be a full, clear, and exact description of the same, reference being had to the accompanying drawings, forming a part of this specification, and to figures of reference marked thereon.

My present invention relates to roll-holders for photographic films, and has particularly for its object to improve and simplify the construction and operation of the film-marking device, whereby the operator is enabled to mark the film at the points where it is to be severed to form the separate negatives; and to this end it consists in certain novelties of construction and combinations of parts, all as will be hereinafter described, and the novel features pointed out particularly in the claims at the end of this specification.

In the drawings, Figure 1 is a sectional view through the casing of a roll-holder, showing the application of my invention thereto; Fig. 2, an enlarged end view of the measuring-roller and marker, the frame being indicated in dotted lines; Fig. 3, a side view of said roll, and Fig. 4 a section on the line $x-x$ of Fig. 2; Fig. 5, a view of the other end of the measuring-roll, showing an indicating device.

Similar figures of reference in the several figures indicate similar parts.

In the present embodiment of my invention I have shown it applied to the form of roll-holder shown in patents granted May 5, 1885, to Eastman and Walker, wherein a removable frame supports the film spool and reel, the section in Fig. 1 being taken close to one side of the casing with said frame shown in elevation; but it is obvious that it could be applied to any form equally well.

The figure 1 represents the holder-casing provided with a front 2, in which is the usual exposing aperture and slide 3, and the back piece 4 is fastened to this casing in the usual or any preferred manner.

5 represents the frame secured to the back 4 by suitable catches, and removable there-

with and therefrom, having at the front the film support or platen 6, and in which the winding-reel 7 and supply-spool 8 are journaled in the manner described in said patent. At the ends of platen 6 are the usual rollers 55 9 and 10, the former designated as the measuring-roller, as it measures off and marks the film into separate exposures. This measuring-roller is preferably provided with the usual prick-points 11 in the surface, 60 adapted to perforate the film at each revolution, and its circumference is such relative to the length of platen 6 that a determined number of revolutions caused by the passage of the film over it will measure off a single 65 exposure the length of the exposing-aperture. At one end the measuring-roller is provided with a suitable indicating device, preferably in the form of a pin 12, arranged, when the roll is rotated, to move a spring 13 away from 70 the under side of platen 6, and by its passage out of the way allow it to snap back against said platen, thus making a click and informing the operator that a quantity of film equal to the circumference of the measuring-roll 75 has been wound over the platen.

The construction of the parts described is substantially the same as that of the roll-holders now on the market, the measuring-roller being so proportioned relative to the 80 length of the exposing-aperture in the casing that four revolutions are necessary to wind forward an exposure of film, necessitating four indications or perforations in the film. These indications being alike, it is necessary 85 to count and sever the film at every fourth mark; and as it is desirable when developing film to have several pieces in the developing-tray at one time, in practical operation it is customary to cut up the film before beginning operations, and should any mistake be made in the counting a number of negatives would be spoiled. This objection can readily be remedied in small-sized roll-holders by making the measuring-roll of such size that 90 a single revolution will mark the film for one exposure; but in large holders this is impracticable on account of the undue increase in the size of the roller, and it is particularly to provide a means for marking the film at the 100

proper place and thereby preventing the liability of cutting the negatives that my present invention is designed.

Near one end of the measuring-roller is provided a small prick-pin 15, extending through the roller and connected at its inner end to a spring 16, formed, preferably, of a small wire lying in a recess below the periphery of the roller, one end being fastened to the roller while the other extends beyond the end of the roller through a slot 17, in a plate 18 secured thereto. The connection between the pin and spring is preferably formed by providing the former with a loop or eye, through which the 15 spring is passed, and the tendency of the latter is such as to keep the sharpened end of the prick-pin below the periphery of the roller and against the end of the slot in the plate 18, which constitutes a stop. The pin 15 is 20 preferably in line with the pins 11 on the roller when the latter are employed, though they may be dispensed with, if desired. Still I prefer to employ them as a means for marking the film, so that, should it be necessary to 25 employ less than a full exposure of film, it may be accomplished and the quantity wound forward determined and marked by their use in connection with the audible indicator, as will be readily understood by one skilled in 30 the art.

As a means for projecting the prick-pin 15 when desired, usually when a single exposure of film has been wound forward I provide an arm or lever 20, pivoted at 21 to the 35 frame and provided at one end with a curved portion 22, arranged in such position relative to the roller and pin as that when the latter is in line with the end of the platen a movement of the arm 20 upward will cause the projection of the pin and the perforation of the 40 paper. This arm is provided on one side with a lug or projection 23, arranged to be operated upon by a pin 24, passing through and guided by suitable perforations in the frame, 45 the movement of the pin being limited by a projection 25, adapted to engage the frame, as shown. For the purpose of operating this rod from the exterior of the casing I arrange a button 26 in a perforation therein, in position to co-operate with the rod end, said button being projected by a spring 27, to which it is secured.

The operation will now be understood. The operator, by means of a suitable key 55 applied to the end of the winding-reel winds forward the film, the click-indicator sounding at each revolution of the measuring-rollers, as usual, and when he has counted four clicks—in the present instance indicating the passage 60 of a full exposure of film—he presses upon button 26, and as at this point the pin 15 is at the end of the platen the arm 20 will operate upon the spring and cause its projection of the pin, thus marking the film by perforating it.

It will be noted that not only is the film

marked at each revolution of the measuring-roller, but may be marked in a distinctive manner at the end of the exposures, or at any multiple of the circumference of said roller, 70 thus giving an absolute and a variable mark.

It will be understood that it is not essential to employ the prick-points 11 at all, but I prefer to use them, or at least one, on the end of the roller opposite the manually-operated point, as it enables the film to be readily severed on straight lines without first creasing it across.

While I have shown my film-marker as applied to the measuring-roller of a roll-holder, 80 I do not desire to be confined to this location of it, as the invention comprehends a marking device capable of operation from the exterior of the casing, particularly when employed with some form of indicator, such as 85 an audible one shown, or a visual one sometimes employed, indicating when a single exposure or definite quantity of film has been wound forward in front of the exposing-aperture.

I claim as my invention—

1. In a roll-holder, the combination, with suitable film winding and supporting devices, of a film-marker operated from the exterior of the holder-casing, substantially as described.

2. In a roll-holder, the combination, with suitable film winding and supporting devices, of a film-marker consisting of a prick-point operated from the exterior of the holder-casing, substantially as described.

3. In a roll-holder, the combination, with suitable film winding and supporting devices, of a film-marker consisting of a prick-point adapted to mark the film from the rear side, 105 operated from the exterior of the holder-casing, substantially as described.

4. In a roll-holder, the combination, with suitable film winding and supporting devices, a roller over which the film passes, and a film-marker thereon normally below the periphery thereof, of a device operated from the exterior of the casing for moving said marker to mark the film, substantially as described.

5. In a roll-holder, the combination, with suitable film winding and supporting devices, a roller over which the film passes, a film-marker and a spring for holding it normally below the periphery thereof, of a device operated from the exterior of the holder-casing for projecting said marker against the tension of the spring, substantially as described.

6. In a roll-holder, the combination, with suitable film winding and supporting devices, of a roller over which the film passes, a film-marker normally below the periphery of the roller, and means for projecting said marker, substantially as described.

7. In a roll-holder, the combination, with suitable film winding and supporting devices, of a roller over which the film passes, having a fixed film-marker near one end, a movable

- marker normally below the periphery of the roller, and means for projecting said movable marker, substantially as described.
8. In a roll-holder, the combination, with suitable film winding and supporting devices, of an indicating device denoting the amount of film wound forward, and a film-marking device operated from the exterior of the holder-casing, substantially as described.
9. In a roll-holder, the combination, with suitable film winding and supporting devices, of a roller over which the film passes having a fixed film-marker, an indicator, and a movable film-marker operated from the exterior of the holder-casing.
10. In a roll-holder, the combination, with suitable film winding and supporting devices, of a roller over which the film passes, a marking-pin thereon, and a spring-pin projecting from the end, the pivoted arm, the rod engaging it, and the spring-projected button operated from the exterior of the holder-casing.
11. In a roll-holder, the combination, with suitable film winding and supporting devices, the marking-pin and the spring-pin projecting from the roller end, the plate on the roller having the perforation for the spring-pin, and means for operating the pin to project the marker, substantially as described.
12. In a roll-holder, the combination, with a casing, a removable frame carrying the film supporting and winding devices, of a film-marker supported on the frame, and a device on the casing for operating said marker from the exterior, substantially as described.
13. In a roll-holder, the combination, with suitable film supporting and winding devices embodying a friction device for retarding the unwinding of the film, an indicator and a film-marker operating on the rear side of the film and actuated from the exterior of the casing, substantially as described.
